(57) **CLAIM**

The ornamental design for a wall mountable holder, as shown and described.

DESCRIPTION

FIG. 1 is a perspective view of a holder showing our new design.

FIG. 2 is a front view of the holder of FIG. 1.

FIG. 3 is a side view of the holder of FIG. 1, the other side being a mirror image thereof.

FIG. 4 is a perspective view of a holder showing our new design.

FIG. 5 is a front view of the holder of FIG. 4; and,

FIG. 6 is a side view of the holder of FIG. 4, the other side being a mirror image thereof.

The broken line showing of partial structure is included for the purpose of illustrating environmental subject matter and forms no part of the claimed design.

1 Claim, 1 Drawing Sheet
